KITE

Alberto A. Concepcion, Detroit, Mich.

Application January 24, 1945, Serial No. 574,296

5 Claims. (Cl. 244—153)

1

The invention relates to kites, and more particularly to an improved kite rigging.

One of the principal causes of kite failure in flight is lack of correct balance. The achievement of precise balance is of especial importance in tail-less kites, i. e., kites which do not carry weighted tail strings or the like to compensate for balancing errors. In kite production, it is virtually impossible to obtain sufficient uniformity in the product to assure correct balance about the center spine. Without built-in balance characteristics it devolves upon the flier to devise corrective measures, and this becomes the source of many failures and much dissatisfaction.

It is an object of my invention to provide an improved kite rigging which overcomes the disadvantages of incorrect balance.

A further object is to provide a kite rigging which facilitates correct balancing adjustment at the factory, and which further facilitates such re-adjustment of the balance as may be needed. These and other objects and advantages of my invention will appear more fully as the description proceeds.

In the drawing:

Fig. 1 is a plan view of one form of kite to which my invention is applicable.

Fig. 2 is a side view of the same kite, showing my improved rigging applied thereto in its preferred form and arrangement.

Fig. 3 is a top view of the kite with the same rigging, illustrating alternative adjustments.

Fig. 4 is a detail cross-sectional view, to an enlarged scale, of the preferred form of slide member for adjustment and locking of the belly string and lateral string.

In accordance with my invention, two cooperating types of adjusting means are employed. One type employs a special slide member for adjusting the length of selected portions of the rigging. The other type employs projecting hook portions on the frame of the kite for selective positioning of the point of attachment of a lateral string to one side or the other of the center of the kite for adjusting the lateral disposition of the belly string.

The design and construction of the kite itself may vary in many of its details, and it is to be understood that the particular form shown is selected merely for illustrative purposes except insofar as concerns the novel features which I will point out particularly. This kite has a frame embodying a center spine 10 (Fig. 1), an oval member 11 secured to the center spine, a curved member 12 likewise secured to the center spine

2

and having its ends tied to the oval member by strings 13. Strings 14 and 15 also may be provided for further reinforcement and to back up the paper or textile frame covering. Diagonal struts 16 are secured to the center spine and to the oval member. The ends of these struts project, as at 17, beyond their intersections with the oval frame member to provide projecting hook portions over which the adjustable loop of a lateral string is slung to provide adjustment of the lateral disposition of the belly string to one side or the other of the center of the kite. A suitable tissue paper or fabric covering 18 is secured over the frame of the kite. (Parts of this covering have been broken away in the drawing to reveal the frame members.)

Referring now more particularly to Figs. 2 and 3, I will describe my preferred form of rigging. It comprises a belly string 19 secured at one end to the frame, as at 20. The other end of the belly string has an adjustable loop passing around the juncture of the spine 10 and oval 11, as at 22. The main string 23 attaches to the belly string in the customary manner. A lateral string 24 joins the belly string adjacent one of its points of attachment to the kite, and terminates in an adjustable loop arranged to be slung over one or the other of the projecting hook portions 17 of the kite frame to provide the adjustment of the lateral disposition of the belly string to which I have referred above.

The adjustable attaching loops of the belly string and lateral string are formed by passing the string back and forth through an apertured slide member 25 which is shown more in detail in Fig. 4. In its preferred form, this slide member has a longitudinal aperture 26 and a transverse aperture 27. This slide may be made of wood, glass, plastic resins or other suitable material. The lateral string 24 passes through the longitudinal aperture 26 and then back through this same aperture to form the attaching loop 28 which, as we have seen, is slung over one or the other of the hook portions 17 formed by the projecting ends of the struts 16. Thus the string passes back and forth through the longitudinal aperture. It also passes through the transverse aperture 27 to lock the string in adjusted position. I prefer that the longitudinal and transverse apertures shall intersect at the center of the slide member. The belly string is rove through one of the slide members 25 in a manner similar to that I have described with reference to the lateral string 24. The length of the belly string at one side of the point of attachment of

3

the main string is thus easily adjusted, just as is the lateral disposition of the belly string through adjustment of the length and position of the lateral string.

Depending upon the relationship of the center of air pressure to the center of the kite as represented by the center spine 10, it may be advantageous to transfer the loop 28 of the lateral string 24 from one projecting hook 17 to the other. Such a condition is represented diagrammatically in Fig. 3 by the dot-dash lines, the alternate positions of the belly string 19, main string 23, lateral string 24 and slide member 25 being shown at 19', 23', 24' and 25' respectively. It will be observed that the center of effort of the main string is thus moved to the left of the main spine. By also adjusting the length of the string 24 (24') the extent to which it is moved to the left can be controlled. Thus the connection shown in dot-dash lines gives a range of adjustment from the center to the left, whereas that shown in full lines gives a range of adjustment from the center to the right. The adjustment is extremely simple and can be made in an instant, and once made, the locking action of the cross apertures of the slide members firmly maintain the adjustment, insuring correct balance in flight.

The terms and expressions which I have employed are used in a descriptive and not a limiting sense, and I have no intention of excluding such equivalents of the invention described, or of portions thereof, as fall within the purview of the claims.

I claim:

1. In a kite rigging, a belly string, a lateral string joining the belly string adjacent one of its points of attachment to the kite, the lateral string being arranged to pass back and forth through an apertured slide member to form a loop for en-

4

gagement with a projecting portion of the kite frame.

5 2. In a kite, a frame having projecting hook portions at each side of the center, a belly string attached to the frame at two points, a lateral string joining the belly string adjacent one of its points of attachment, the lateral string being arranged to pass back and forth through an apertured slide member to form a loop for engagement with one or the other of said projecting hook portions for adjustment of the lateral disposition of the belly string.

10 3. A construction as set forth in claim 2 which is further characterized by a second apertured slide member through which the belly string passes back and forth for adjustment of the distance from one of its points of attachment to its juncture with the main string.

15 4. In a kite having a belly string, means incorporated in the belly string at one side of its point of attachment to the main string for adjusting the length of the belly string, and means for adjusting the lateral disposition of the belly string adjacent one of its points of attachment to the kite.

20 5. In a kite having a belly string, means incorporated in the belly string at one side of its point of attachment to the main string for adjusting the length of the belly string, and means for adjusting the lateral disposition of the belly string adjacent one of its points of attachment to the kite, said last-named means comprising an apertured slide member and a string joining the belly string adjacent one of its points of attachment and passing through said slide member to form a loop for engagement with a projecting portion of the kite frame.

30 ALBERTO A. CONCEPCION.
